UNITED STATES PATENT OFFICE

EDWIN H. BURROWS, OF CLEVELAND, OHIO, ASSIGNOR OF ONE-HALF TO WORTHINGTON HOYT, OF CLEVELAND HEIGHTS, OHIO

EXPLOSIVE COMPOSITION

No Drawing.

Application filed May 2, 1931. Serial No. 534,710.

This invention relates to new and useful improvements in explosive compounds and more particularly to an improvement on the explosive compound for which United States

5 Letters Patent were granted to Frank R. Burrows and Joseph G. Burrows, April 22, 1919, No. 1,301,646.

The object of the invention is to provide an explosive compound of high power and 10 destructive strength and which at the same time will be safe to handle and can be economically produced.

A further object of the invention is to provide an explosive compound which will not 15 be subject to freezing, which can only be exploded by detonation and which will not give off injurious fumes when exploded.

Another object of my invention is to provide an explosive compound of such a character that repeated charges of the same may 20 be safely used without having to wait for the material which is being worked on to cool off.

Further advantages of my explosive compound will be fully set forth in the following 25 specification.

In carrying my invention into practice, I provide an explosive compound consisting essentially of the following ingredients or their 30 substantial equivalents, to wit:

	Parts
Ammonium perchlorate-----	54
Barium nitrate-----	29.5
25 Aluminum powder-----	1.5
Aluminum granules, about 30 mesh-----	9
Resin-----	3
Paraffine wax-----	2
Brown wax-----	1
40 Total-----	100.00

The ingredients are mixed in an ordinary incorporating mill, the barium nitrate being first introduced and the mill kept in action 45 for a period of about 30 minutes to affect its reduction to the desired degree of fineness, after which the ammonium perchlorate, the aluminum powder, the aluminum granules and the resin are introduced and the mass is 50 ground and agitated for a further period of

twenty minutes. The paraffin wax and the brown wax may be then added to the mixture either in a melted state or dissolved in a suitable volatile solvent.

From the mill, the compound thus prepared, is passed to a sifter consisting of a revoluble screen drum covered by a wire mesh cloth, through which the powder discharges as the drum revolves. A number of brass or other hard balls are placed in this drum 55 to break up all hard lumps and to disintegrate all the material to the desired degree. The powder is then filled into paper cartridge cases, preferably, by a filling machine. The ends of the cases are then folded over and 60 dipped in melted paraffin. The explosive in the form of cartridges is then ready for use.

This explosive compound possesses great explosive power, is non-freezing and consequently the dangers experienced in the operations of thawing out other explosives are avoided. This compound is absolutely safe from explosion by attrition or friction or by fire or by blows or concussion from tools or the like. It does not give off any injurious 75 gases as substantially all injurious gases are consumed in the explosive action. The explosive may be manufactured with absolute safety at all times and may be used in either wet or dry holes and will explode only by 80 detonation, using a detonator of not less than No. 6 strength. It may be simply and cheaply manufactured, allows holes to be charged and mis-fires to be treated without risk, and since it is not explosive by heat, a sprung 85 hole may be charged therewith without danger and without the necessity of waiting until the bore is cooled, thus obviating the loss of time and danger incurred in the use of ordinary explosives.

Through employing a high proportion of ammonium perchlorate and by substituting exceedingly fine powdered aluminum together with a small quantity of resin for the alpha-trinitrotoluene, of the Burrows patent 95 heretofore referred to, I am able to provide an explosive compound of greater strength and very much safer to manufacture and operate with than can be produced by following the teaching of the said Burrows patent. 100

The use of fine powdered aluminum makes it possible to very definitely and positively control the explosive force and rapidity of action of the explosive compound. That is 5 by slightly altering the proportion of the aluminum powder the compound can be readily adapted to various fields of operation. To those skilled in this art it is well known that an explosive compound suitable for use 10 in gold mines would be very destructive and wasteful in coal mines. By changing the amount of my fine aluminum powder I can make my explosive compound so that it will have the proper explosive force and the required rapidity of action for any class of work. This cannot be as positively and 15 readily done with alpha-trinitrotoluene without sacrificing the safety element.

The water-cooled process aluminum employed in this improved explosive compound is prepared by pouring the molten aluminum on to a rapidly revolving wheel which dashes it in the form of a spray into cold water. This process produces large jagged-surfaced 20 particles or granules and gives the cooled particles very sharp points or edges which render the material susceptible to rapid ignition and combustion. This material is 25 then ground, or is ground during the operation, to pass through a screen having about 30 meshes per linear inch, the resulting particles are porous and hence in a highly reactive state. Aluminum prepared in any 30 other way does not give, in explosive work, 35 the complete satisfaction and advantage afforded by the aluminum as above stated. The form in which the aluminum is used in 40 this compound is of material importance, and when used in connection with the other ingredients set forth, provides a compound which possesses the desirable advantage before stated.

The high quantity of ammonium perchlorate used in my compound is very important. The ammonium perchlorate forms a 45 perfect combination with the fine aluminum powder and the resin, and the intensity of the explosion is much greater than where a relatively less quantity of ammonium perchlorate is employed with alpha-trinitrotoluene.

When this compound is exploded it gives off a quantity of smoke of an absolutely 50 harmless nature as the intensity of the explosion causes the consumption of all harmful gases. The compound has a very desirable 55 and unique ripping action in blasting large masses of rock, and in the tests made, is found to be of greater disruptive strength than the 60 explosive compound produced by the aforementioned Burrow's patent formula.

What I claim is:

1. An explosive compound consisting substantially of 54 parts ammonium perchlorate 65 29½ parts barium nitrate, 1½ parts fine

aluminum powder, 9 parts aluminum granules, and 3 parts resin.

2. An explosive compound consisting substantially of 54 parts ammonium perchlorate, 29½ parts barium nitrate, 1½ parts fine 70 aluminum powder, 9 parts aluminum granules, 3 parts resin, 2 parts paraffin wax, and 1 part brown wax.

In testimony whereof I affix my signature. 75
EDWIN H. BURROWS.
